LINEMAN'S CLIMBERS

Raymond C. Bailey, Fredericksburg, Va.

Application April 24, 1933, Serial No. 667,745

5 Claims. (Cl. 36—60)

The object of my invention is to provide novel and approved linemen's climbers which can be used more comfortably with greater security than devices of this type heretofore invented. It is a special object of my invention to provide a novel form of foot plate; to provide novel means for pivotally connecting said foot plate to the stirrup; to provide a novel heel guard member; and to provide improved means for strapping the device to the foot, without interfering with flexibility in use. It is also an object of my invention to provide a device which can be manufactured at least possible expense while retaining the novel features disclosed. I attain these and other objects of my invention by the mechanism illustrated in the accompanying drawings, in which—

Figure 1 is a side elevation of the preferred form of my invention;

Fig. 2 is a rear elevation of same with a portion of member 1 broken away;

Fig. 3 is a top plan view of the invention with member 1 shown in section and with a portion of the straps 16 and 20 broken away;

Fig. 4 is a vertical section on line 4—4 of Fig. 3;

Fig. 5 is a side elevation of modified form of the invention;

Fig. 6 is a vertical section on line 6—6 of Fig. 5;

Fig. 7 is a sectional view on a similar section line of a modified form of the invention having a conventional type of stirrup, and

Fig. 8 is a section on line 8—8 of Fig. 6.

Like numerals designate like parts in each of the several views.

Referring to the accompanying drawings, I provide a metal leg strap 1 having a conventional leather protective pad 2 secured to the top thereof, and having a conventional leather strap secured to the pad and upper end of the strap 1 for fastening the device to the leg. I provide a suitable spur 4 riveted or otherwise suitably fastened to the lower end of strap 1. At the lower end of metal leg strap 1 I provide a cylindrical stirrup 5 on which is pivotally mounted a foot plate 6. The foot plate 6 consists of an instep 7, a heel 11 and a sole 17. It extends under and supports substantially the entire foot.

On the instep 7 I provide depending flanges 8, as shown in Figs. 3 and 4, having apertures 9 through which the cylindrical stirrup 5 extends. The foot plate 6 is held in place on the stirrup by the collar 10, affixed to member 5 in any suitable manner as by a pin. On the heel portion 11 of the foot plate 6 I provide a leather riser 12, the purpose of which is to raise the heel of the shoe so that the instep of the foot will not rest too heavily

on the instep of the foot plate. Both members 11 and 12 are provided with apertures 13. Likewise the sole 17 of the foot plate is provided with an aperture 18. The purpose of the apertures 13 and 18 is to decrease the weight of the device to prevent slipping while walking on the ground.

As shown in Fig. 1, the heel 11 is provided with upturned flanges 14, to which a heel guard plate 15 is securely fastened. I provide suitable heel straps 16 attached to the heel guard plate 15 as shown in Figs. 1 and 2. The sole plate 17 is provided with upturned flanges 19, to which suitable toe straps 20 are secured.

Referring to Figs. 5 and 6 of the drawings, there is illustrated a modification of the invention in which a metal leg strap 1 having a flat stirrup member 21 is provided.

In Fig. 7 is shown a conventional metal strap having the usual flat stirrup member 21 and the conventional upturned strap holding member 22. This is illustrated to show how my foot plate 6 may be applied to a conventional type of stirrup by providing apertures 26 in the stirrup to receive rivets to engage the bearings.

As shown in Figs. 5—8 inclusive, I provide a trunnion 23 secured to the bottom of the instep 7 by brazing 24 or like suitable means. The trunnion 23 is pivotally mounted in bearing 25. Bearings 25 are secured in place by rivets or the like which are mounted in apertures 26 provided in the stirrup plate 21 as shown in Figs. 6 and 7. I provide retaining collars 27 affixed to the ends of trunnion 23 as shown.

In use the climber is attached to the leg by strap 3 and the foot plate 6 is fastened on the foot of the wearer by the heel straps 16 and toe straps 20. As the foot plate 6 is pivotally mounted at the instep on the stirrup as shown, a necessary freedom of movement is given in the use of the device which facilitates climbing and also makes it much more comfortable and convenient for the linemen. The spur 4 is used to aid in climbing in the usual manner. By providing the foot plate with the apertures 13 and 17, the weight of the device is materially lessened and it also functions to prevent slipping while walking on the ground. With this device a lighter weight shoe or boot can be used and the design of the device protects the shoe while in use.

It is to be understood that the foot plates are made in lefts and rights of suitable shape to substantially conform to the shape of the particular foot to which they are attached.

What I claim is:

1. In linemen's climbers, the combination of a metal leg strap having a conventional spur, pad and fastening strap, a cylindrical stirrup formed on the lower end of the leg strap, a foot plate mounted for free pivotal movement on the stirrup, said foot plate extending under the instep, the entire bottom surface of the heel and the major portion of the sole of the boot or shoe.
- 10 2. In linemen's climbers, in combination with the device defined in claim 1, a heel guard plate secured to the heel of the foot plate and adapted to engage around the heel of the boot or shoe, heel straps attached to said heel guard plate, and toe straps attached to the foot plate.
- 15 3. In linemen's climbers, the combination of a metal leg strap having a conventional spur, pad and fastening strap, a stirrup on the lower end of said strap, a foot plate, a trunnion affixed to the underside of the foot plate at the instep, bearings in which the trunnion pivots, said bearings being affixed to the stirrup, and retaining means on the ends of the trunnion.
- 20 4. In linemen's climbers, the combination of a metal leg strap having a spur, pad and fastening strap, a cylindrical stirrup formed on the lower end of the leg strap, a foot plate extending under the entire area of the heel and having free pivotal movement, instep and a considerable portion of the sole, means pivotally connecting the instep of the foot plate with the stirrup, the foot plate having apertures in the heel and sole to prevent slipping while walking on the ground.
- 25 5. In linemen's climbers, the combination of a metal leg strap having a spur, pad and fastening strap, a stirrup formed on the lower end of the leg strap, a foot plate extending under substantially the entire bottom of the foot except the toe portion, a heel guard plate secured to the heel portion of the foot plate, means pivotally connecting the instep of the foot plate with the stirrup, means for attaching the foot plate to the foot or shoe, and a riser in the heel portion of the foot plate to prevent too much weight resting on the instep of the foot plate.

RAYMOND C. BAILEY.
